(57) **CLAIM**

The ornamental design for a connector capable of connecting a plurality of plugs, as shown and described.

DESCRIPTION

FIG. 1 is a front view of a connector capable of connecting a plurality of plugs showing our new design;

FIG. 2 is a rear view thereof;

FIG. 3 is a left view thereof;

FIG. 4 is a right view thereof;

FIG. 5 is a top plan view thereof;

FIG. 6 is a bottom plan view thereof; and,

FIG. 7 is a perspective view thereof.

The broken line portion of the figure drawings is included to show unclaimed subject matter only and forms no part of the claimed design.
